UNITED STATES PATENT OFFICE.

HENRY C. HARRIS, OF HIGGINSVILLE, MISSOURI.

KNEE-SHOE.

SPECIFICATION forming part of Letters Patent No. 395,228, dated December 25, 1888.

Application filed September 3, 1888. Serial No. 284,508. (No model.)

To all whom it may concern:

Be it known that I, HENRY C. HARRIS, a citizen of the United States, residing at Higginsville, in the county of Lafayette and 5 State of Missouri, have invented a new and useful Knee-Shoe for Coal-Miners who labor on their knees mining thin veins of coal; and I hereby give a full description of the same, reference being had to the accompanying 10 drawing and to letters marked thereon, which form a part of this specification, and which drawing is a perspective view of the knee-shoe and appendages.

In the accompanying drawing, the letter A 15 indicates a concave piece of wood, metal, rubber, or paper, which may be termed the "shoe-cup," made to fit over a person's knee when in a kneeling position, there being a low place or notch, B, in the edge to receive 20 the shin just below the knee-pan, and there is a flange, C; round the shoe-cup A to hold a piece of leather for the knee to stand on, the shoe-cup A being made out of wood, metal, rubber, or paper.

25 The letter D indicates a piece of leather or other fabric with a string or wire, E, braided into the out edge of the leather D and tied firmly under the flange C, the leather being stretched tight enough to sustain a person, so 30 the knee cannot strike the bottom of the shoe-cup A or come in contact with any hard substance, and forms what may be termed a "suspended knee-bearing." By extending the flange C round the notch B and inclosing 35 the notch B with the leather D the shoe-cup A can be made water-tight to keep the knees dry.

There is a thin board, F, which extends to the instep to protect the shin and attached to 40 the shoe-cup A with hinges G G, so a person can walk without misplacing or rocking the shoe-cup A, and which is also to hold the

shoe-cup A up in its place, and in the lower end of the board F there is a notch, H, with a strap, I, stretched across the notch H to prevent galling the instep. There are also cleats J J on each edge of the board F, and a strap, K, stretched across the cleats J J to prevent galling the shin.

The letters L L indicate straps fastened 50 round the ankle and leg below the knee, and M M straps fastened round the leg above the knee.

The letter N is a piece of leather fastened to the shoe-cup A and to one of the straps M 55 to protect the top of the knee, and there are also ears O O, fastened to the shoe-cup A, which extend up on each side of the knee, and straps or sticks P P, fastened to the straps M M on each side of the leg, which are connected to the ears O O with pivots or hinges Q Q, which permit the knee to bend back and forth, while also holding the shoe-cup A in its proper place on the knee.

What I claim as my invention, and desire to 65 secure by Letters Patent, is—

1. The concave shoe-cup A, having a notch, B, provided with the flange C, the pieces of leather D N, the string or wire E, and the straps for securing the parts to the leg, substantially as shown and described.

2. The combination of the concave shoe-cup A, the board F, the hinges G G, the ears O O, sticks P P, the pivots or hinges Q Q, secured to the shoe-cup A, and straps for fastening the parts to the leg, substantially as shown and described.

Dated at Higginsville, Lafayette county, Missouri, July 25, 1888.

HENRY C. HARRIS.
